UNITED STATES PATENT OFFICE

167,447

PLATE OR SIMILAR ARTICLE

Helen M. Dost, Glenview, Ill., assignor to Onondaga Pottery Company, Syracuse, N. Y., a corporation of New York

Application November 13, 1951, Serial No. 17,362

Term of patent 14 years

(Cl. D44—15)

To all whom it may concern:

Be it known that I, Helen M. Dost, a citizen of the United States, residing at Glenview, Cook County, State of Illinois, have invented a new, original, and ornamental Design for a Plate or Similar Article, of which the following is a specification, reference being had to the accompanying drawing, forming a part hereof.

The sole figure is a top plan view of a plate or similar article, showing my new design. The characteristic features of the design reside in the figure situated at the center of the plate and the annular floral ring surrounding said figure, as shown.

I claim:

The ornamental design for a plate or similar article, as shown and described.

HELEN M. DOST.
